TERMINAL PLUG FOR SHADE ROLLERS
James A. Anderson, Muskegon, Mich., assignor to
Breneman, Inc., a corporation of Ohio
Filed Oct. 21, 1965, Ser. No. 500,406
8 Claims. (Cl. 160—323)

ABSTRACT OF THE DISCLOSURE

A terminal plug for insertion into the open end of a tubular shade roller, in which such terminal plug is provided with an annular band seatable along the length of the plug to effectively determine the extent of telescoping engagement of the plug within the tubular roller by abutting the end of the roller. The annular band has a flat internal periphery at least in part, the edges of which define squared corners, and the terminal plug has annular grooves along its length for engaging the band by its squared corners. Two embodiments of the band are disclosed, one being of elastomeric material, preferably for use with a wooden terminal plug, and the other being a split ring of moldable plastic material, preferably for use with a molded plastic terminal plug. Either form of terminal plug has a shoulder at its forward end for retaining the annular stop ring on the plug and preventing it from being forced over the forward end thereof; in the case of the wooden plug, the shoulder is a sheet metal cap having a radial lip extending rearwardly of the plug at an acute angle and having a length sufficient to engage the band outwardly of its mean diameter when the band is forced against it, for positive retention of the band under such conditions.

This invention relates to roller assemblies for window shades and the like, and more particularly to a removable terminal plug for use at one end of such a roller which provides a series of positively indexed, adjustable positions between the plug and the shade roller which vary the effective length of the roller assembly in predetermined and definite increments which are not disturbed by the application of forces to the end of the roller which exceed those normally expected in typical shade operation, such as may arise when the roller is dropped directly upon its end.

For some time it has been the usual practice of the shade roller industry to produce window shades and rollers in several standard lengths, which are chosen to fit a group of window widths which have been selected as those most frequently encountered in building construction. This produces a troublesome and ever-present problem, since in actual practice a great many windows are not of a standard dimension. Further, even where windows are nominally of one of the standard sizes, the shade mounting brackets which have been installed very often are spaced a distance that is either slightly greater than or slightly less than the exact standard dimension of the shade roller. Thus, actual experience has proven that more often than not, adjustments in the effective overall length of a roller must be made before the shade can be mounted to the actual width of a particular window.

The dealer from which the shade is purchased usually makes the adjustment in its length by selecting the next larger standard size of shade which he has in stock, and trimming both the shade and the roller to the required dimension. The dealers are usually equipped with special trimming machines for this operation, but there are many possible sources of human error between the measurement and the trimming of the roller, and it frequently occurs that the final resulting shade

2

roller does not in fact accurately fit the window for which it was intended, and instead has been cut a small amount short of the precise size which is needed. Further, it also frequently occurs that the casement measurements of particular windows which appear upon casual examination and measurement to be of a standard size are in actuality a small amount wider than the apparent nominal standard dimension. In all of these instances, it is necessary for the consumer himself to somehow slightly adjust the length of the roller to meet the exact circumstances which he encounters when he attempts to mount it for use. Thus, in order to provide for a completely satisfactory installation, shade rollers should be produced with a structure which allows the overall length to easily be extended or reduced over a relatively small range, so that the length of the roller may be adjusted accordingly.

One type of structure which in general has provided satisfactory shade roller length adjustment is a removable terminal plug which fits into the gudgeon pin end of the roller. Such a plug may be removed to permit trimming of the roller when this is required, and the plug also provides for length adjustment of the overall roller assembly if the extent to which the plug is inserted in the end of the roller may be varied when desired. Various schemes have previously been suggested for varying the engagement of the plug within the roller and for securing the plug relative to the roller at various degrees of insertion, since the plug and roller definitely must be relatively secure at various adjusted positions if continuous satisfactory performance is to be provided. However, most such previous schemes have had inherent limitation which adversely affected their operation.

For example, when placed in an extended position, many such plugs tend in operation to slip backward into the roller, and even a small amount of such slippage soon allows the entire roller assembly to drop out of its mounting brackets. Also, the adjustment of a plug within the roller is frequently difficult to accomplish or extremely tedious and painstaking. Further, experience indicates that shade rollers are often inadvertently dropped upon one end, typically the plug end. This creates an extremely annoying problem, since in the case of most removable terminal plugs the plug is forcibly driven completely within the end of the shade roller tube in which it is inserted. The result is that the terminal plug is made difficult or impossible to remove from the roller, since it becomes tightly wedged therein in a position which is not accessible from outside the roller. While the roller tube itself is not often damaged merely by dropping the assembly in this manner, the tube is likely to become damaged by either the forcible insertion of the plug thereinto, or else by attempts at removing the plug. This is also likely to damage the plug, since the gudgeon pin may be pulled from it or else structural damage to the pin or the plug may be caused by probing at it or pulling it in attempting to remove it from the roller tube.

It is a major object of the present invention to provide a removable terminal plug for shade rollers which effectively resolves the problems indicated above. The shade roller assembly in which the present terminal plug is used may be quickly and easily adjusted in length by a series of definite incremental adjustments. More importantly however, each of the adjusted positions of the roller assembly is positive and is indexed against any subsequent inadvertent changes, whether these result from normal operating forces applied to the roller, or from unusual or unexpected forces, such as result when the roller assembly is dropped upon one end.

The foregoing major objectives and the advantages provided thereby, together with numerous other objects and

advantages, will be understood by those skilled in the shade roller and shade equipment art upon further consideration of the ensuing specification and its appended claims, particularly when taken in conjunction with the accompanying illustrative drawings setting forth preferred embodiments of the invention.

In the drawings:

FIG. 1 is a side elevational view, partially in section, of a first embodiment of the terminal plug of the invention;

FIG. 2 is an enlarged, fragmentary, central section of a portion of the device of FIG. 1 showing details thereof;

FIG. 3 is an enlarged, fragmentary, central section of the embodiment of FIG. 1, showing operational details thereof;

FIG. 4 is a greatly enlarged, fragmentary, central section of one end of the structure of FIG. 1, showing further details thereof;

FIG. 5 is a side elevation in central section of a second embodiment of the invention; and

FIG. 6 is a lateral perspective view of a portion of the structure of FIG. 5.

Briefly stated, the present invention provides a terminal plug for shade rollers of the type characterized by an open tubular end. The terminal plug has a generally cylindrical body portion which is frictionally insertable into the tubular end of the roller, and an expandable stop ring of resilient material having a normal inside diameter smaller than the outside diameter of the cylindrical body but sufficiently expandable to be telescoped thereover. When the stop ring is not expanded, it seats about the body of the plug with sufficient frictional engagement to resist movement lengthwise of the plug under most normal operating forces exerted endwise against the roller, and serves to provide an abutment for the tubular end of the roller which limits the insertion of the plug thereinto. When the stop ring is circumferentially expanded it is adjustable along the length of the plug to vary the insertion thereof into the roller tube. The plug has a shoulder structure located at the outward end thereof opposite the end which is inserted into the roller, and this shoulder has an effective diameter greater than that of the plug body, to prevent the stop ring from being forced over and off from the said outward end of the plug. The plug further has means located along its length for engaging at least a portion of the stop ring when the same is seated about the plug, to inhibit the movement of the stop ring along the said plug under forces which exceed those experienced under usual or typical operation, including such forces as are produced by dropping the roller assembly upon its terminal plug end.

Referring now in more detail to the drawings, a first and preferred embodiment **10** of the present terminal plug is illustrated in FIGS. 1-4 inclusive. This embodiment basically includes a generally cylindrical body portion **12**, a resilient stop ring **14** seated about the body **12**, and a disc-like cap **16** at the end of the body, including a gudgeon pin or nail **18** of a typical type.

The body portion **12** of this embodiment is preferably a solid wooden member, and it has a series of buttress-shaped annular grooves **20** formed along its length at the end having the cap **16** and gudgeon **18**. As FIG. 2 best illustrates, each of the buttress grooves **20** has the edge **21** thereof which is positioned nearest the outer or gudgeon pin end of the plug formed substantially normal to the surface of the plug and also normal to the longitudinal axis thereof. A ramp-like portion **22** of each buttress groove extends rearward from the bottom of the normal edge **21** to the outer surface of the plug, and a brief portion **23** of the plug surface spaces the ramp portion **22** from the next succeeding normal edge **21**. In a specific preferred configuration, the normal edge **21** has a depth of about $\frac{1}{32}$ inch, the length of the ramp **22** is about $\frac{1}{8}$ inch, and the length of the surface portion **23** is about $\frac{1}{32}$ inch.

The stop ring **14** most preferred for use with the body

portion **12** just described is a flat, resilient, elastomeric band, as for example of synthetic rubber. The width of the band or ring **14** is preferably about $\frac{1}{4}$ inch, and the band should have a normal inside diameter which is slightly smaller than the outside diameter of the body portion **12** but the band should be sufficiently resiliently expandable to be telescoped over the body. Thus, when the band or ring is not expanded it will seat snugly about the body and the frictional engagement therewith will be sufficient to resist movement of the band lengthwise of the plug under normal operating forces exerted endwise of the roller assembly. That is, when the body portion **12** of the plug is inserted into the open end of an appropriate shade roller, the stop ring **14** seated about the body portion forms an abutment for the tubular end of the roller to limit the degree of insertion of the plug thereinto, and the frictional engagement of the stop ring and plug will effectively resist a first degree of force exerted endwise of the roller which might otherwise move the ring relative to the body and change the effective overall length of the roller.

When the stop ring **14** is intentionally expanded, it is adjustable along the length of the terminal plug, and may be placed in the region of the buttress grooves **20** formed therein (FIG. 3). In this area, the natural or inherent resilience of the elastomeric stop ring causes its forward portion to contract against the ramp edge **22** of a particular buttress groove, with the forward edge of the band directly abutting the normal edge **21** of that particular groove. Under these circumstances, the stop ring or band **14** is effectively indexed in position, and a considerably greater degree of longitudinal force must be exerted against it in order to force it out of and over the particular buttress groove with which it is engaged than is the case when the ring is merely seated about the cylindrical portion of the plug body (as seen in FIG. 1). However, since the ring is preferably slightly wider than the length of each buttress groove, it may be easily grasped by the fingers and expanded outwardly to deliberately move it from one particular groove to another.

The end cap or disc **16** of the terminal plug **10** is preferably a circular sheet metal structure which is stamped to have the cross sectional shape shown in FIG. 1. Specifically, the outer perimeter or lip **24** of the cap is formed to extend away from the gudgeon pin end of the plug and toward the end thereof which is inserted into the roller tube. Thus, if the stop ring or band **14** is placed or somehow driven to the outer or gudgeon pin end of the plug, as shown in FIG. 4, it comes into contact with a shoulder provided by the extending perimetral portions **24** of the cap. Since the stop ring is preferably a resilient elastomer, if it is placed under extensive endwise force by the end of a roller tube and driven against the extending shoulder of the end cap, the band will deform by bowing outward over the central area of its width.

The present inventor has determined that if the outer periphery of the end cap is merely vertical, the elastomeric band may become sufficiently distorted under load to slip over the shoulder and completely off the terminal plug. It is for this reason that the lip portion **24** of the end cap **16** is formed at the angle **26** shown in FIG. 4, which in the most preferred form should preferably be approximately 25 degrees. In this form the angularly extending lip will cradle the edge of the elastomer band and retain it in place about the body of the terminal plug. Thus, the plug will not be driven into the tubular end of the roller by a force of this nature, and instead the elastomer band will act as a shock absorber to cushion and dissipate such a force, even though this force might be so great as to initially dislodge the stop ring from one or more of the buttress grooves and move it into contact with the shoulder or lip provided by the end cap.

Due to the manufacturing economies which may presently be achieved through the molding of plastic substances, it may be desired to embody the concepts in-

volved in the terminal plug 10 just discussed in a moldable plastic form. An embodiment 110 of this nature is shown in FIGS. 5 and 6, wherein the cylindrical body portion 112 is tubular in nature, and a terminal cap 116 and gudgeon pin 118 are integral with the body portion 112 so as to be moldable as a single unit. A terminal plug of this nature should preferably be slightly conical in form, i.e., flared outwardly slightly toward its inner end, opposite the gudgeon pin. Further, the body portion 112 should have at least one and preferably two longitudinal slits or separations 111, so that the actual diameter of the body may be decreased by resiliently contracting its flared end to insert the plug into a tubular roller. Thus, when the plug is released within the roller it will resiliently expand toward its normal diameter and thereby increase the frictional engagement between plug and roller tube. The split and flared molded plastic terminal plug body 112 is preferably formed from the plastic known commercially as "Delrin," due to the superior resiliency and plastic memory exhibited by this substance.

The stop ring 114 for the terminal plug 110 may also be formed of moldable plastic, and preferably has a nominal inside diameter that is smaller than the nominal outside diameter of the plug body. The stop ring 114 is circumferentially split (see FIG. 6) so that it may be resiliently expanded to slip over the body 112, where it may be released to resiliently grip the surface of the body. It will be noted that while the outer surface of the stop ring is flat, the inner surface is not, and instead has a downwardly-projecting ridge 115 which preferably extends completely about the inner circumference of the ring. Like the plastic terminal plug body 112, the plastic stop ring 114 is also preferably formed from Delrin, for the above-described qualities which it possesses.

Like the first embodiment 10 of the terminal plug seen previously, the embodiment 110 of FIGS. 5 and 6 is also annularly grooved at the end near the gudgeon pin. However, when the molded plastic embodiment is used together with the plastic stop ring 114, the annular grooves 120 in the plastic body need not have the buttress shape which has been previously described, but instead they may have the generally open V-shape illustrated in FIG. 5. This is true since unlike the elastomeric stop ring 14, the more rigid plastic stop ring 114 will not contract its forward edge into the annular groove. Instead, the inner ridge 115 of the plastic ring will firmly engage the central portion of each groove, so that the ring is retained against lengthwise movement relative to the plug in an analogous manner. That is to say, the combination of the resilience of the Delrin ring together with its internal ridge 115 acts to retain this stop ring upon the body of a terminal plug somewhat more securely than the mere elasticity alone of the resilient rubber ring 14 which has no internal ridge, and consequently while the buttress form of annular groove is extremely useful in connection with a resilient rubber stop ring, the buttress form of annular groove is not strictly necessary when a split plastic ring of the aforementioned type, with an internal ridge or the equivalent, is used. Nonetheless, the plastic type stop ring may be used with the buttress type grooves if desired, although the flat rubber or elastomer stop ring when used with the V-type annular groove does not give an equivalent performance.

The molded plastic embodiment of the terminal plug, like the wood embodiment previously discussed, also has a shoulder structure at its gudgeon pin end for preventing the stop ring from being forced over the end and completely off the body of the plug. This shoulder is designated 117 in FIG. 5, where it will be noted that unlike the lip 24 of the previous cap structure 16, the shoulder 117 need not be positioned at an angle relative to the body of the plug, but instead may extend generally radially or normally thereof. This is true since the more rigid molded plastic stop ring does not noticeably deform under the application of endwise force and consequently

does not tend to bow out and slip over the extending shoulder. Thus, all that is required to retain such a stop ring on the body of the plug is a radially-extending shoulder for direct abutment by the stop ring.

Having now described in detail the structure of two specific embodiments of the present terminal plug construction, the assembly of each with an associated shade and roller will likely be entirely apparent. All that is required is to insert the inner end of the terminal plug opposite the gudgeon pin into the open tubular end of the roller, to the extent that the stop ring seated about the surface of the terminal plug comes into abutting contact with the end of the roller tube. This produces a sturdy and stable roller assembly which may be mounted in a pair of spaced conventional mounting brackets for rotary operation of the shade.

The present form of terminal plug provides several noteworthy and desirable advantages over the basic removable plug construction, however, which previous construction have failed to do. Firstly, the resilient stop rings 20 may be forcibly expanded and adjusted along the length of the plug body to vary the insertion of the plug into the roller and thereby change the effective overall length of the roller assembly. When seated upon the plug, either form of stop ring will maintain the desired and selected overall length by resisting movement along the plug under normal operating forces applied endwise of the roller assembly. However, in the area of the annular grooves in the plug, the stop ring is positively indexed 25 at selected incremental length adjustments, so that even forces exceeding normal operating forces cannot dislodge the stop ring and change a selected adjustment.

If the roller assembly should be dropped on its gudgeon pin end, as frequently happens in actual usage, the 30 terminal plug will not be driven into the roller to render the roller assembly useless, since the engagement of the stop ring by the annular groove will ordinarily prevent any such occurrence. Further, even if unexpectedly high impacts or other forces are applied to the terminal 35 plug end of the roller assembly, the plug will still not be driven completely into the roller due to the presence of the stop ring and its abutment with the shoulder structure at the end of the plug, which effectively serves to prevent the stop ring from being forced over the end of the terminal plug. In such an event, either form of stop 40 ring described heretofore helps in absorbing the unexpectedly large shock due to its resilient nature. Further, such extensive forces will not damage either type stop ring since the elastomeric ring resiliently deforms itself 45 readily under the shock to dissipate it, while the high compression qualities of the Delrin ring cause it to deform less while nonetheless absorbing the forces exerted 50 upon it.

It is conceivable that after becoming familiar with the 55 principles and the underlying concepts of the invention set forth heretofore, those skilled in the shade roller equipment art will choose to implement these concepts in slightly different embodiments or to vary or modify the specific embodiments which are disclosed hereinabove. 60 All such embodiments and modifications as incorporate the concepts of the invention and utilize its fundamental principles are therefore to be considered as within the scope of the claims appended herbelow, unless these claims by their language specifically state otherwise.

I claim:

1. A terminal plug for shade rollers of the type characterized by an open tubular end, said plug comprising: a generally cylindrical body frictionally insertable into said tubular end; an expandable stop ring of resilient elastomeric material having a normal inside diameter smaller than the outside diameter of said body but sufficiently expandable to be telescoped thereover; said stop ring when not expanded seating about said plug with sufficient frictional engagement to resist movement lengthwise of the 70 plug under a first degree of force exerted endwise of said 75 plug.

roller; said stop ring when seated about said plug forming an abutment for the tubular end of the roller to limit the insertion of said plug therewith; said stop ring when expanded being adjustable along the length of said plug; a shoulder structure located at the outward end of said plug opposite the end which is inserted into said roller; said shoulder having an effective diameter greater than that of said plug body and preventing said stop ring from being forced over said outward end and off said plug; and a plurality of recesses formed in said body at different positions along the length thereof, each for engaging at least a portion of said stop ring to inhibit the movement thereof along said plug at each of said positions under forces exceeding said first degree, to thereby index said ring at predetermined and selectable increments; each of said recesses having an edge positioned toward said outer plug end, such edges formed normal to said surface and normal to the longitudinal axis of the plug; said shoulder structure including a portion extending radially of said plug body and having a lip at its extremity which extends at an acute angle relative to the body toward that end of said plug which is inserted into said tubular roller, said portion having an extent sufficient to cause said lip to engage said stop ring at a point radially outwardly of the mean diameter thereof; said elastomeric ring when forced against said extending lip deforming toward the vertex of said acute angle for positive retention of the ring upon the plug body under a second degree of said force exceeding said first degree thereof.

2. The terminal plug defined in claim 1, wherein said shoulder structure is a circular end cap disc, said portion is the central part of said disc, and said lip is formed around the peripheral extremity of said disc.

3. A terminal plug for shade rollers of the type characterized by an open tubular end, said plug comprising: a generally cylindrical body frictionally insertable into said tubular end; an expandable stop ring of resilient material having a normal inside diameter smaller than the outside diameter of said body but sufficiently expandable to be telescoped thereover; said stop ring when not expanded seating about said plug with sufficient frictional engagement to resist movement lengthwise of the plug under a first degree of force exerted endwise of said roller; said stop ring when seated about said plug forming an abutment for the tubular end of the roller to limit the insertion of said plug therewith; said stop ring when ex-

5

10

20

25

30

35

panded being adjustable along the length of said plug; a shoulder structure located at the outward end of said plug opposite the end which is inserted into said roller; said shoulder having an effective diameter greater than that of said plug body and preventing said stop ring from being forced over said outward end and off said plug; and means located on said body for engaging at least a portion of said stop ring when seated at a plurality of positions along the length of said plug to inhibit the movement of said ring along said plug at each of said positions under forces exceeding said first degree and thereby index said ring at predetermined and selectable increments; said stop ring being a split snap ring of molded plastic material having internally-projecting portions for engagement by said means.

4. The terminal plug defined in claim 3, wherein said means includes a plurality of recesses formed in the surface of said body, each having one edge positioned toward said outer plug end which is formed normal to the longitudinal axis of the plug.

5. The terminal plug defined in claim 4, wherein said recesses are annular grooves around the circumference of said plug body.

6. The terminal plug defined in claim 3, wherein said body is of molded plastic material and said shoulder structure is molded integrally therewith.

7. The terminal plug defined in claim 6, wherein said body is of "Delrin" plastic, is tubular in form, is flared outwardly toward the end which is inserted into said roller, and is split longitudinally from the said inserted end so as to be diametrically expandable within said roller.

8. The terminal plug defined in claim 7, wherein said means include a plurality of annular grooves formed circumferentially in the surface of said body and normal to the longitudinal axis thereof.
